UNITED STATES PATENT OFFICE.

EDWARD GURNEY, OF TORONTO, CANADA.

DESIGN FOR A RADIATOR.

SPECIFICATION forming part of Design No. 22,543, dated June 13, 1893.

Application filed February 24, 1893. Serial No. 463,632. Term of patent 7 years.

To all whom it may concern:

Be it known that I, EDWARD GURNEY, of the city of Toronto, in the county of York and Province of Ontario, Canada, a subject of the Queen of Great Britain, have invented and produced a new and original Design for Radiators, of which the following is a specification, reference being had to the accompanying drawing, forming part thereof.

10 The drawing is a perspective view illustrating my design for radiators.

My design consists of a radiator having five loops or legs, the broad outer loop on each side being rounded off and extending over the top; the bas-relief frieze and dado of acanthus leaf scrolls with interlacing spirals growing from the leafage and extending into a plain surface, thus terminating the scrolls, and having between the different loops short

20 round horizontal bars.

A, is the outer loop, the inner loops being marked B.

C, is the bas-relief frieze, D, the dado and the bars E. The tops and bottoms of the openings between the loops are curved or 25 arched as shown at E, thus forming a graceful finish to the junction of the loops at top and bottom. This, with the additions of the bars E, the outer and inner loops and the leaf and scroll ornamentation above referred to, 30 makes the design new and attractive.

What I claim is—

The design for a radiator, herein shown and described.

Toronto, February 16, 1893.

EDWARD GURNEY.

In presence of—

J. EDW. MAYBEE,
W. G. McMILLAN.
